US0D1101514S

(12) **United States Design Patent** (10) **Patent No.:** **US D1,101,514 S**
(45) **Date of Patent:** **** Nov. 11, 2025**

(54) **EATING UTENSIL**

(71) Applicant: **MASONTOPS IP HOLDINGS INC.**,
Toronto (CA)

(72) Inventors: **Michael Bacher**, Toronto (CA); **Philip Baron**, Toronto (CA); **Brett Molnar**,
Toronto (CA)

(73) Assignee: **MASONTOPS IP HOLDINGS INC.**,
Toronto (CA)

(**) Term: **15 Years**

(21) Appl. No.: **29/904,954**

(22) Filed: **Oct. 13, 2023**

Related U.S. Application Data

(63) Continuation of application No. 29/891,192, filed on
May 2, 2023, now Pat. No. Des. 1,006,556, which is
a continuation of application No. 29/799,844, filed on
Jul. 16, 2021, now Pat. No. Des. 988,088.

(57) **CLAIM**

The ornamental design for an eating utensil, as shown and described.

DESCRIPTION

FIG. 1 is top and front perspective view of an eating utensil showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view;

FIG. 7 is a bottom plan view; and,

FIG. 8 is a bottom and rear perspective view thereof.

The dashed broken lines in the figures illustrate portions of the eating utensil that form no part of the claimed design.

1 Claim, 7 Drawing Sheets
